(57) **CLAIM**

I claim, the ornamental design for a sawhorse stacking bracket, as shown and described.

DESCRIPTION

FIG. 1 is a perspective view of a sawhorse stacking bracket.

FIG. 2 is a front view thereof.

FIG. 3 is a top view thereof.

FIG. 4 is a side view thereof.

FIG. 5 is a bottom view thereof.

FIG. 6 is a perspective view thereof, showing my new design in full lines with broken lines showing of environmental association matter being for illustrative purposes only and forming no part of the claimed design; and,

FIG. 7 is a perspective view thereof, showing my new design in full lines with broken lines showing of environmental association matter being for illustrative purposes only and forming no part of the claimed design.
